(57) **CLAIM**

The ornamental design for a tray for shopping cart as shown and described.

DESCRIPTION

FIG. 1 is a top, rear perspective view for a tray for shopping cart showing our new design;

FIG. 2 is a top, rear perspective view of the tray for shopping cart and assemblies thereof of FIG. 1, with unclaimed portions outside of the right and left boundary lines in FIG. 1 being removed and the scale being enlarged as comparison to FIG. 1;

FIG. 3 is a bottom, front perspective view thereof;

FIG. 4 is a top view thereof;

FIG. 5 is a bottom view thereof;

FIG. 6 is front view thereof;

FIG. 7 is a rear view thereof;

FIG. 8 is a right side view thereof; and,

FIG. 9 is a left side view thereof.

In the drawings, the broken lines show portions of a tray for shopping cart which form no part of the claimed design. The features shown in long-dash-short-dash bolded broken lines indicate the bounds of the claimed design and otherwise form no part of the claimed design. The cart shown in broken lines in FIG. 1 show environment and form no part of the claimed design.
